UNITED STATES PATENT OFFICE.

RUPERT SCHEFBAUER, OF JERSEY CITY, NEW JERSEY, ASSIGNOR TO THE STERLING ARC LAMP COMPANY, OF NEW YORK.

DESIGN FOR AN ARC-LAMP CASING.

SPECIFICATION forming part of Design No. 29,893, dated December 27, 1898.

Application filed October 22, 1898. Serial No. 694,344. Term of patent 7 years.

To all whom it may concern.

Be it known that I, RUPERT SCHEFBAUER, a citizen of the United States, residing at Jersey City, in the county of Hudson and State of New Jersey, have invented and produced a new and original Design for Arc-Lamp Casings, of which the following is a specification, reference being had to the accompanying drawings, forming a part thereof.

In the drawings illustrating my invention, Figure 1 is a side elevation of the lamp-casing. Fig. 2 is a view in plan.

In the drawings, Fig. 1, A A represent a cylinder the lower portion of which is slightly enlarged and flares out in the form of a rounded flange E. Upon the upper end of the cylinder is an ornamental collar, cornice, or mold-

ing B, and at the lower end and at a point where it leaves the perpendicular to form the flange E is another ornamental collar or molding D. At a point between the collars B and D is a third collar or ornamentation C.

The leading feature of my design is the configuration of the casing.

I claim—

The design for a lamp-casing as herein shown and described.

In witness whereof I have hereunto set my hand this 20th day of October, 1898.

RUPERT SCHEFBAUER.

Witnesses:

MICHAEL WALLSTEIN,
ANDREW FOULDS, Jr.
